No. 874,861.

PATENTED DEC. 24, 1907.

R. POCKMAN.
SOLDERING IRON.
APPLICATION FILED MAY 31, 1906.

UNITED STATES PATENT OFFICE.

RAYMOND POCKMAN, OF YOLO, CALIFORNIA.

SOLDERING-IRON.

No. 874,861.

Specification of Letters Patent.

Patented Dec. 24, 1907.

Application filed May 31, 1906. Serial No. 319,524.

To all whom it may concern:

Be it known that I, RAYMOND POCKMAN, a citizen of the United States, and a resident of Yolo, in the county of Yolo and State of California, have invented a new and Improved Soldering-Iron, of which the following is a full, clear, and exact description.

The invention relates to a soldering iron of that class in which a liquid fuel reservoir is combined with the iron and certain devices for gasifying the said fuel, so that the gas may be burned with a Bunsen flame to heat the iron.

The invention resides in certain special features of construction and combination of parts, and all will be fully set forth herein-after and particularly pointed out in the claims.

Reference is to be had to the accompanying drawings which illustrate as an example the preferred form of my invention, in which drawings

Figure 1 is a longitudinal section of the invention on the line 1—1 of Fig. 2; Fig. 2 is a rear end elevation with parts in section on the line 2—2 of Fig. 1; Fig. 3 is a detail view of the mixer or Bunsen tube; Fig. 4 is a detail view of the burner tube; Fig. 5 is a detail view of the head of the iron; and Fig. 6 is a sectional view showing a modification of the generator tube.

10 indicates the gasoline or other volatile liquid fuel reservoir, which is provided with a perforate jacket 11 of suitable material, 35 and has heads 12 and 14 screwed on its respective ends. Fastened to the head 12 is a screw closure 15 which carries within the reservoir 10 a cylinder 16. In this cylinder a piston 17 operates, the rod 18 of which is 40 joined to a finger piece 19 outside of the plug 15, and adapted to be engaged with undercut stops 20, thus holding the finger piece 19 and its connections releasably against operation. The rod 18 fits loosely 45 in the plug 15 to permit the movement of air past the rod into the cylinder, and the cylinder is provided at its inner end with a discharge 21 into the reservoir 10, which discharge is controlled by a suitable valve 22 50 seating against return flow into the cylinder. By means of this device the finger piece 19 may be released at will from the stops 20, and the piston 17 operated to force air into the reservoir 10, thus causing the volatile liquid fuel therein to be forced from the

reservoir into the generator and burner devices to be hereinafter described.

The head 14 at the end of the reservoir 10 opposite the head 12 carries interiorly a perforated hood 23, and this incloses the inner 60 end of the tube 24 which extends through the head 14 and is fitted with a perforated cap 25. The cap 25 is of such a size as to allow the tube 24 to be removed from the reservoir 10 without releasing the head 14 from 65 the reservoir. Said tube 24 is connected with the generator tube 26 which projects forward from the outer end of the tube 24.

27 indicates a needle valve commanding the discharge opening in the end of the generator tube. If desired, the generator tube 26 may be provided with pockets 28 communicating with the interior of the tube and adapted to receive the liquid fuel, to increase the rapidity and extent of heating of the same 75 by bringing the fuel into closer proximity with the head of the burner. The stem of the valve 27 has a slide 29 connected therewith, and this slide is formed with a diagonal surface 30 engaged by a screw pin 31 which operates in a laterally projecting boss 32 carried by the tube 26, and the outer end of which has a thumb wheel 33 for operating the pin whereby the valve 27 may be advanced at will toward closed position. From the 85 slide 29 a rod 34 extends, and this rod bears the pressure of the spring 35 which acts on the needle valve 27 to open the same.

36 indicates a coiled wire or its equivalent, which is placed in the tube 24 between the 90 slide 29 and spring 35 to form a tortuous or obstructed passage for the gasoline or other fuel, thus obstructing the flow of the fuel and offering greater heating surface to the same.

Attached to the outer end of the generator tube is a cup 37. This cup surrounds the end of the tube and carries the perforated Bunsen or mixer tube 38 which projects from the end of the generator tube in line therewith. Fastened to the cup 37 is the perforated shell 39 forming the burner chamber, and this in turn carries the head 40 of the soldering iron, which is provided with passages 41 discharging backward from the point of the iron for carrying off the products 105 of combustion.

In the use of the invention, sufficient pressure is accumulated in the reservoir 10 to cause the oil to flow into the generator tube. The cup 37 should then be filled with a vola- 110

tile hydrocarbon or the equivalent saturated, if required, in a mass of absorbent material, and this lighted and burned in the usual way to heat the generator tube sufficiently to cause the fuel therein to be transformed into a gas. The valve 27 should then be opened and this gas or vapor passing into the Bunsen tube 38 mixes with the air therein and may then be ignited to burn with a blue flame within the shell 39, heating the iron 40 and permitting the same to be used easily and efficiently. The pump should be operated from time to time to maintain the necessary pressure in the reservoir, thus causing the fuel to be constantly advanced to the generator tube and to pass the needle valve into the Bunsen tube in the form of a vapor or gas.

Having thus described the preferred form of my invention, what I actually claim and desire to secure by Letters Patent is:

1. A soldering iron, comprising a reservoir for liquid fuel, an air pump in the reservoir, a perforated hood within the reservoir at the inner end thereof, an outlet tube secured to the inner end of the reservoir and extending into the hood, a generator tube secured to the outlet tube, a spring-pressed valve for the generator tube, means for operating the valve, a cup secured to the generator tube and having a Bunsen tube projecting centrally therefrom, a perforated shell secured to the cup and projecting beyond the same, and a head secured to the shell.

2. A soldering iron, comprising a reservoir for liquid fuel, means for forcing liquid fuel

therefrom, an outlet tube extending into the reservoir and having means therein for obstructing the flow of the liquid fuel, a generator tube secured to the outlet tube and projecting beyond the reservoir, a valve for the generator tube, means for operating the valve, a Bunsen tube projecting beyond the end of the generating tube, a cup at the base of the Bunsen tube, a perforated shell secured to the cup and inclosing the Bunsen tube, and a head secured to the shell, and having rearwardly inclined discharge passages.

3. In a soldering iron, a reservoir for liquid fuel, means for forcing the fuel from the reservoir, an outlet tube projecting into the reservoir, a generating tube projecting beyond the end of the reservoir, a valve for the generator tube, said valve being provided with a stem projecting into the outlet tube and having a member provided with an inclined surface, a spring surrounding the stem in the outlet tube, a tubular boss on the generator tube, an adjustable pin in the boss and engaging the inclined surface of the member of the valve stem, a burner carried by the generator tube, and a head adjacent to the burner.

In testimony whereof I have signed my name to this specification in the presence of two subscribing witnesses.

RAYMOND POCKMAN.
